UNITED STATES PATENT OFFICE.

FRANCIS BLAKE, OF WESTON, MASSACHUSETTS.

SWITCH-BOARD FOR TELEPHONE-EXCHANGES.

SPECIFICATION forming part of Letters Patent No. 392,403, dated November 6, 1888.

Application filed August 10, 1888. Serial No. 282,431. (No model.)

To all whom it may concern:

Be it known that I, FRANCIS BLAKE, of Weston, in the State of Massachusetts, have invented a new and useful Improvement in Switch-Boards for Telephone-Exchanges, of which the following is a specification.

In the multiple switch-board now generally used in large telephone-exchanges there is apportioned to each operator a certain number of subscribers' lines, normally grounded, each through a separate annunciator at the section of the board under the charge of such operator, but each branching to a spring-jack at the same section. When the drop of an annunciator falls, the ground of the line connected therewith is thereby cut out, and the line remains connected with the spring-jack, there being a separate spring-jack as well as separate annunciator for each line belonging to that section. This same section of the board is also provided with an enormous number of other spring-jacks or plug-holes, or similar terminals, a separate one in metallic connection with each separate subscriber's line centering at the exchange, other than the lines first mentioned as grounded at the particular section—that is, each section of the board is provided with a spring-jack, or its equivalent, for and in metallic connection with each line normally grounded at such section, and with a separate spring-jack, or its equivalent, for and in metallic connection with each and every other line belonging to the exchange, and it follows that by a connecting-cord provided with suitable plugs at either end the operator at each and every section can connect any line entering the exchange at his section with any other line belonging to the exchange.

The construction and operation of the multiple switch-board are attended with certain difficulties, which it is the object of my invention to remedy. Among other things, I wish to avoid the great cost attending its construction. In the multiple switch-board, as stated above, each line-wire entering the exchange must be provided with a separate branch wire leading to each separate section of the board system. In practice it is found that each operator can make the required connections in answer to calls of about one hundred subscribers, and it is found advantageous to have two

adjoining operators work their two sections as one. Accordingly, there are two hundred subscribers' lines normally grounded through annunciators and connected with separate spring-jacks, or equivalents, at the two sections, and the two sections together are provided with a separate spring-jack, or its equivalent, for every line entering the exchange, other than the two hundred. Thus in a board constructed for an exchange of five thousand subscribers, each of the five thousand subscribers' wires has twenty-four branches leading to twenty-four double sections of the board, and thus there is required a multitude of branch wires and soldered connections. These I do away with. Again, since each line has so many branches with free ends at each of the several double sections, it is necessary that the operators at each double section shall be provided with apparatus to test whether any required line to be called is already in use through any of its branches, and the testing apparatus in general use requires additional separate branch wires leading from each wire that enters the exchange to each double section of the board. The necessity for such testing apparatus is obviated by my invention. Again, when an exchange has outgrown the multiple switch-board originally provided or contemplated the original plant must be taken down, and practically an entirely new board built, for it is practically impossible to provide for a substantial increase without losing the benefit of the former construction, whereas a board originally constructed and operated according to my invention may be increased in capacity to any extent by mere addition to the original plant.

A further object of my invention is to lighten the labor of the operators in making connection between subscribers. How this is accomplished sufficiently appears in the description of the invention given below. It may be well to state here, however, that in practicing my invention the operators who make the connections do not answer the original calls of subscribers. On the contrary, they answer second calls. My system requires the co-operation of two operators to make a connection between two lines, and it is necessary that both of these operators shall carry

on telephonic conversation with the "calling" subscriber. Further, it may be observed, although it will hereinafter more fully appear, that in the switch-board constructed according to my system the lines of subscribers are grouped together not as "calling-lines" but as lines "to be called." In this respect my system differs from any switch-board system heretofore in use, and in this, as will hereinbelow appear, lies its chief advantage.

The apparatus employed in practicing my invention, besides line-wires and telephones, consists, essentially, in, first, a central or distributing board provided with terminals and 15 grounded annunciators, one of each in each subscriber's line; second, a number of connecting-tables through one or another of which each subscriber's line passes to its said terminal and grounded annunciators at the said distributing-board, there being in each of said lines a spring-jack at that connecting table through which the line thus passes, and, third, connecting-strips between said distributing-board and each of said connecting-tables, each 20 of said strips being provided with a connecting-cord or equivalent terminal at either end, and also with an annunciator at its respective connecting-table.

In the apparatus represented in the drawings both the annunciators of the main lines at the distributing-table and those of the strips just mentioned at the connecting-table are grounded in branches of the line or strip, respectively, and the terminals of the main-lines 30 at the distributing-board as well as the terminals of the strips—*i.e.*, the connecting-cords—are open. A slight modification of this construction will hereinafter be referred to as a modification of my invention.

In the drawings, Figure 1 illustrates in diagram so much of the apparatus employed as it is necessary to exhibit for a full understanding of my invention. Fig. 2 illustrates in diagram the manner in which the capacity of 40 the system represented at Fig. 1 may be increased. Figs. 3 and 4 show details of construction and modifications.

B is the distributing-board. As shown at Fig. 1, it is supposed to be of a capacity sufficient for one thousand subscribers, and is in 50 two sections, one for subscribers' lines numbered from 1 to 500, and the other for subscribers' lines numbered from 501 to 1,000.

T and T' are connecting-tables. Although 55 but two are shown at Fig. 1 there will be in practice one connecting-table for every hundred subscribers' lines, and they will be known as "table No. 0," "table No. 2," "table No. 5," &c.

The subscribers' lines entering the exchange 60 are marked L with the number of the line—thus L₁, L₅₂₄, &c. To avoid confusion, but few are shown. Each subscriber's line enters at its appropriate connecting-table, and, passing 65 through a spring-jack, one for each line at that table, goes to the distributing-board, where it branches, one branch leading to a

grounded annunciator and the other to an open terminal in the distributing-board. The spring-jacks at the connecting-table are marked J, with the number of the line J', J₅₂₄, &c. In like manner A, with the number of its line, designates an annunciator at the distributing-board. *w*, with the number of the line, represents that portion of the main line lying between the spring-jack at the connecting-table and the distributing-board.

G is a common ground for these annunciators. The terminals in the distributing-board consist of the metallic linings of the plug-holes 80 there shown; or they may consist of spring-jacks. They have the numbers of their respective lines.

S^o is a group or series of metallic strips or wires running from the distributing-board to the connecting-table No. 0. S⁵ is a like group running to the connecting-table No. 5. In practice there is a separate group of these metallic S-strips between the distributing-board and each connecting-table, and it will be found 90 in practice that five of such strips in each group will be ample in an exchange of one thousand subscribers, and it is believed that the larger the exchange shall be the fewer of such strips will be required between the distributing-table and each connecting-table.

Each S-strip terminates at the distributing-board in a connecting-cord, C, the free end of which, or the plug on the free end of which, is adapted to be inserted in any of the plug-holes 100 on the distributing-board. In like manner each S-strip has at its connecting-table a similar connecting-cord, c, whose plug is adapted to be inserted in any of the spring-jacks at that table. A branch from each strip terminates at its respective connecting-table in a grounded annunciator—one for each strip. In practice the S connecting strips of each series are numbered 1 2 3 4 5, and the corresponding annunciators at each table are likewise 110 numbered 1 2 3 4 5. The common ground for the annunciators at each connecting-table is g. The respective operators at each section of the distributing-table and at each connecting-table are furnished with the usual telephone apparatus of table-operators. (Not shown.)

The manner in which the invention is practiced will be understood from a description of the condition of the apparatus shown at Fig. 1. Line 524 has called, the drop of annunciator 524 has fallen, and that annunciator has lost its ground. The operator at section 2 of the distributing-table has plugged his telephone apparatus into terminal hole 524 of distributing-board and ascertained that line No. 1 is wanted. Disconnecting his telephone apparatus he has plugged C-cord 1 (any unoccupied C-cord) into hole 524, and the drop of annunciator 1 at table No. 0 has fallen, and that annunciator has lost its ground. Then 120 the operator at connecting-table No. 0 has connected connecting-cord c of strip s' with his own telephone apparatus, and in turn has 125 asked the calling subscriber what connection 130

is wanted, and the calling subscriber has again replied that line 1 is wanted. Finally the operator at the connecting-table has plugged connecting-cord *c*' into spring-jack *J'*, and the desired connection between line 524 and line 1 is accomplished. The plug on the end of connecting-cord *c* has one insulating face and has cut out *W' A'* and terminal 1 at distributing-board.

- 10 The C-cord used as above might normally be connected with plug-hole 524 and form the open terminal of line 524 and in the operation be plugged into the strip without departing from my invention. In fact, although the construction would cost more, the work of the operator at the distributing-table would be a little more expeditious if all the cords were normally attached to the distributing-board, since he would use the same cord to connect his telephone with the calling-line that he uses to connect the calling-line with the strip—just as the operator at the connecting-table uses the same cord to connect his telephone with the calling-line that he uses to connect the calling-line with the desired line. In either case these cords are weighted and drawn behind their strips or board, as the case may be, so that their plugs or ends with which a connection is to be made are within ready reach of the operator.
- 20 (See Fig. 3.) It is evident also that without departing from my invention the annunciators, whether at the distributing-table or at a connecting-table, might be grounded through the terminal, the latter being slightly modified in construction, or the spring-jack form being used, and remain in circuit whenever the lines are connected. Such a construction is shown at Fig. 4, where the terminal is in the form of a spring-jack, *J*⁵²⁴. One face of the connecting-cord on plug *C* is here of insulating material, and when inserted in the spring-jack cuts off the ground *g*' and leaves the annunciator in the working line. A modification of like nature will leave the annunciators at the connecting-table in the line.
- 25 It is thought that an operator at the distributing-board will have sufficient work in attending to five hundred lines, and that an op-

erator at a connecting-table will have sufficient work in attending to one hundred lines; 50 but the capacity of the switch-board may be increased to any extent by making a new section of distributing-board for every additional five hundred subscribers' lines, providing a new connecting-table for each additional one 55 hundred subscribers, and furnishing a set of connecting-strips between each section of the distributing-board and each connecting-table. It has been stated above, however, that a set of five strips leading to each table is sufficient 60 for a distributing-board having provision for one thousand subscribers' lines. Therefore but a single set of strips is needed between each connecting-table and two adjoining sections of the distributing-board of the capacity 65 of five hundred lines each, as shown in Figs. 1 and 2.

Fig. 2 shows the switch-board of Fig. 1 increased to a capacity of two thousand subscribers. Further description of Fig. 2 is unnecessary, unless, perhaps, it may be well to say that the general system of lettering and numbering used in Fig. 1 has been followed in Fig. 2.

I claim—

In a switch-board for a telephone-exchange, the combination, with the line-wires, of, first, the distributing-board provided with terminals and grounded annunciators, one of each for each line-wire; second, connecting-tables through 80 which the said line-wires or subscribers' lines pass in groups to their respective said terminals and annunciators at the said distributing-board, there being in each of said lines a spring-jack at that connecting-table through 85 which the line thus passes, and, third, connecting-strips between said distributing-board and each of said connecting-tables, each of said strips being provided with a connecting-cord or similar terminal at each end, and also with 90 an annunciator at its respective connecting-table, substantially as described.

FRANCIS BLAKE.
